UNITED STATES PATENT OFFICE

MAGGY BESANCON DE WAGNER, OF PARIS, FRANCE, ASSIGNOR TO LENTHERIC, INCORPORATED, OF NEW YORK, N. Y., A CORPORATION OF NEW YORK

DESIGN FOR A BOTTLE

Application filed March 21, 1930. Serial No. 34,990. Term of patent 3½ years.

To all whom it may concern:

Be it known that I, MAGGY BESANCON DE WAGNER, a citizen of the Republic of France, residing in the city of Paris, France, have invented a new, original, and ornamental Design for a Bottle, of which the following is a specification, reference being had to the accompanying drawing, forming a part thereof.

In the drawing,
Fig. 1 is a perspective view of my bottle.
Fig. 2 is a top view thereof.
Fig. 3 is a bottom view thereof.

I claim:

The ornamental design for a bottle substantially as shown.

MAGGY BESANCON DE WAGNER.
